(57) **CLAIM**

The ornamental design for a headgear kit, as shown and described.

DESCRIPTION

FIG. 1 is a right side view of a headgear kit with the protrusion portions not attached;

FIG. 2 is a top view thereof;

FIG. 3 is a left side view thereof;

FIG. 4 is a rear view thereof;

FIG. 5 is a bottom view thereof;

FIG. 6 is a front view of the headgear kit of FIG. 1 with the protrusion portions attached;

FIG. 7 is a right side view thereof;

FIG. 8 is a top view thereof;

FIG. 9 is a left side view thereof;

FIG. 10 is a rear view thereof;

FIG. 11 is a bottom view thereof; and,

FIG. 12 is a front view thereof.

The headgear kit is meant to be worn by a person with a skull abnormality and the protrusion(s) deters the person from sleeping on that side of their skull.

The broken lines in the figures depict environmental subject matter only and form no part of the claimed design.
